UNITED STATES PATENT OFFICE

112,439

DESIGN FOR A HEAT RADIATOR SECTION

Arthur E. Paige, Philadelphia, Pa.

Application May 28, 1938, Serial No. 77,453

Term of patent 14 years

To all whom it may concern:

Be it known that I, Arthur E. Paige, a citizen of the United States, residing at Philadelphia, in the county of Philadelphia and State of Pennsylvania, have invented a new, original, and ornamental Design for Heat Radiator Sections, of which the following is a specification, reference being had to the accompanying drawings, forming part thereof.

In said drawings:

Fig. I is an end elevation of a heat radiator section, showing my design.

Fig. II is an elevation of the right hand side of said section as shown in Fig. I.

Fig. III is an elevation of the upper side of said section as shown in Figs. I and II.

Fig. IV is an elevation of the lower side of said section as shown in Figs. I and II.

The concentric lines in Fig. I represent a central cylindrical tube which extends throughout the entire section. The space between the dotted lines in Fig. II is the cylindrical cavity in said tube. In such a section as shown, molded of translucent "oven glass", said space between the dotted lines in Fig. II appears darker than the exterior of said tube and shaded as a cylinder.

I claim:

The ornamental design for a heat radiator section, as shown and described.

ARTHUR E. PAIGE.
